UNITED STATES PATENT OFFICE

HOWARD W. HINDES, OF WORCESTER, MASSACHUSETTS, ASSIGNOR TO THE WASHBURN COMPANY, OF WORCESTER, MASSACHUSETTS, A CORPORATION OF MASSACHUSETTS

DESIGN FOR A HANDLE

Application filed December 1, 1932. Serial No. 46,268. Term of patent 14 years.

To all whom it may concern:

Be it known that I, HOWARD W. HINDES, a citizen of the United States, residing at Worcester, in the county of Worcester and Commonwealth of Massachusetts, have invented a new, original, and ornamental Design for a Handle, suitable for kitchen and household tools or utensils, such as cake turners, can openers, egg beaters, forks, ice picks, knives, potato mashers, spoons, strainers and similar articles, of which the following is a specification, reference being had to the accompanying drawing, forming part thereof, in which:—

Fig. 1 is a perspective view of a handle showing my new design, looking at one side and end.

Fig. 2 is a similar perspective view of the handle, looking at the opposite side and end.

Fig. 3 is a transverse sectional view along the line 3—3 of Fig. 1, looking in the direction of the arrow.

As shown in the drawing, the handle consists of a body of reversely tapered form, the axial cross-section of which is circular, raised beads extending around the body near its ends, with one bead located in the concavity between reversely tapered portions of the body.

I claim,

The ornamental design for a handle, as shown and described.

Dated this 18th day of November 1932.

HOWARD W. HINDES.
